JOHN H. DERBY, OF SCARSDALE, NEW YORK

HIGH-LOW GRAVITY TANK ALARM FLOAT

Application filed June 26, 1928. Serial No. 288,383.

This invention relates to alarms and signal devices such as are employed for giving an indication of the level of liquid in a tank.

It is an object of the present invention to provide a simple and reliable device for giving a signal when the level of liquid in a tank is above or below certain predetermined levels.

Another object of the invention is to protect various parts of the device from corrosion or injury.

The invention will be more clearly understood by reference to the accompanying figure of the drawing which illustrates a preferred embodiment of the invention.

The figure is a diagrammatic view of the apparatus.

In the form of the device as illustrated a float 1 is located in the tank and is preferably 20 in the form of a hollow cylindrical chamber formed of light metal, such as brass or bronze tubing tinned or chromium plates to resist corrosion. The float 1 is provided with a central opening 2 through which a hollow

25 Monel metal rod 3 passes so that the float is free to move up or down upon the rod 3 as a guide. This rod is provided with a stop 4 to limit the downward movement of the float member and is provided with a stop 5 to prevent upward movement of the float member beyond predetermined points. The rod 3 passes through a heavy tubular member 9 supported by the bracket 10 and secured thereto by means of the cast iron bushing 11 and a locknut 12. A guide 8 is located in the lower end of the member 9 and is preferably 30 in the form of a bakelite bushing threaded into the tubular member 9 as shown. The rod 3 extends above the member 9 and into

40 a casing 15 containing the signal means, to be hereinafter described. A second guide 16 in the form of a bakelite bushing threaded into the upper end of the tubular member 9 is also provided. The rod 3 preferably carries a stop member 45 to limit the upward movement of the rod and nuts 46 to limit the lower movement of the rod.

The upper end of the member 9 is threaded into the casing 15 so as to support the casing. 45 The upper end of the tubular rod 3 is pro-

vided with upper and lower engaging blocks 17 adapted to engage a bakelite bushing 18 which is slidable on the rod 3. The bushing 18 has a reduced central portion 19 which is engaged by the forked ends 20 of a bronze operating bar 22. The bar 22 is pivoted about the bearing 23 and is provided at its opposite end with a slot 24 engaged by the springs 26 and 27. The lower spring 26 acts as a counterbalance for the weight of the rod 3 and the elements secured thereto while the upper spring 27, when tensioned, urges the operating bar 22 back to its normal position. The spring 27 is preferably adjustable by means of the threaded member 29 supported by the bracket 30 secured to the casing 15 and is normally slack so that the balance of the rod 3 and its associated parts will not be destroyed by splashing of the mercury in the chamber 38 or by jarring of the tank or 70 the casing 15. The operating bar 22 is provided with a slot 24 in order that a very small amount of play of the spring 27 may take place.

The operating bar 22 is provided at its 75 central portion with a bracket 35 to which spring clips 36 and 37 are secured. A glass chamber 38 containing a conducting liquid such as mercury, is mounted in the spring clips 36 and 37 and is provided with three 80 spaced contact members which form a part of an electric circuit to be used in giving an alarm when the level of the liquid in the tank is greater or less than the predetermined levels. The central contact 40 may be termed a common and is continually submerged or in contact with the mercury in the chamber 38. The end contacts 41 and 42 are positioned slightly above the level of the mercury in the tube so as to be out of contact with the mercury when the tube 36 is in its normal position but in position to complete a circuit through the mercury and the common whenever the chamber 38 is tilted by movement of the operating bar 22. If a closed alarm circuit is employed the contacts 40, 41 and 42 may all be in contact with the mercury when the chamber 38 is in the normal position and this contact may be broken by 95 100

tilting of the chamber by the operating bar 22 is horizontal or in the desired position. The casing 15 may then be sealed shut. If then the level of the liquid in the tank varies so that the float does not bear against either stop member 4 or 5 no alarm will be given but if the level of the liquid should become too low the float 2 will bear against the stop 4 on the rod 3 and instead of being submerged in the liquid in the tank to a normal depth it will be supported by the rod 3 so that the balance of the mechanical system will be destroyed, tilting the operating rod 22 and chamber 38 so that the contact member 42 will make contact with the mercury, or if a closed alarm circuit is used the contact 41 will break its contact with the mercury and an alarm will be given, indicating that the level of the liquid in the tank is below the predetermined level.

In order to prevent corrosion of the various parts of the mechanism and to prevent the access of vapors from the tank to the casing 15 where they might cause corrosion of the various parts, a cylindrical casing 50 is provided supported by the bushing 11 and extending downwardly from the bracket 10 below the level of the liquid in the tank. The casing 50 is preferably formed of brass tubing and is of slightly larger diameter than the float member 1. The casing 50 prevents the passage of vapors from the tank through the bushings 8 and 16 into the casing 15 and limits the area from which the vapors could rise to the very small surface of the liquid between the float 1 and the casing 50. In order to further insure that no corrosion of the parts enclosed in the casing 15 may occur the space 51 between the rod 3 and the tubular member 9 may be filled with wool or other moisture-absorbing material. If desired, a small vent 53 may be provided in the upper end of the casing 50 to permit the air displaced by movement of the piston 40 and the liquid within the casing 50 to pass into and out of the casing.

The casing 50 performs several very important functions besides limiting the surface area from which vapors can arise to corrode the parts of the mechanism. Thus, it is seen that if the liquid in the tank should be set in motion by a pump or for any other reason, the float 1 will not be affected by the currents produced in the tank but will float on the undisturbed liquid within the casing 50 and give an accurate indication of the level of the liquid in the tank. The casing also limits the lateral movement of the float member 1 and prevents it from bumping 55 against the rod 3 and giving a false indication of the level of the liquid in the tank.

The casing 50 also acts as a protecting member during shipment of the mechanism so as to prevent damage to the float member 60 or bending of the rod 3.

The operation of the device is as follows: The stop members 4 and 5 are adjusted to the desired positions and secured in place. The spring 26 is adjusted so as to balance the rod 3 and the spring 27 adjusted until it is under no tension when the operating bar 22 is horizontal or in the desired position. The casing 15 may then be sealed shut. If then the level of the liquid in the tank varies so that the float does not bear against either stop member 4 or 5 no alarm will be given but if the level of the liquid should become too low the float 2 will bear against the stop 4 on the rod 3 and instead of being submerged in the liquid in the tank to a normal depth it will be supported by the rod 3 so that the balance of the mechanical system will be destroyed, tilting the operating rod 22 and chamber 38 so that the contact member 42 will make contact with the mercury, or if a closed alarm circuit is used the contact 41 will break its contact with the mercury and an alarm will be given, indicating that the level of the liquid in the tank is below the predetermined level.

On the other hand, if the level of the liquid in the tank should become too high the float will engage the stop 5 and be submerged beyond the normal depth, causing the rod 3 to be moved upward, tilting the operating bar 22 and giving the desired signal.

From the foregoing description it will be seen that a simple level indicator is provided which is sensitive and so protected from corrosion and deterioration that it may be safely and effectively used for long periods of time without adjustment and on tanks such as emergency water tanks which are not subject to frequent inspection.

What is claimed as new is:

1. A signal device responsive to liquid level, which comprises a float, a vertical casing surrounding the float so as to protect it from local disturbances in the liquid, but open to the tank above and below the float so as to permit said float to respond accurately to changes in the general level of the liquid, a mercury switch connected into a circuit so as when closed to give a high level alarm, a mercury switch connected into a circuit so as to give a low level alarm, means connecting said float to said mercury switches adapted to tilt the high level alarm switch so as to close its contacts when the float is raised to a position corresponding to a liquid level at the upper limit of permissible variation, and to tilt the low level switch so as to close its contacts when the float drops to a position corresponding to a liquid level at the lower limit of permissible variation, means for resiliently maintaining said switches in open contact position while said float is between said limiting positions adapted to yield to the forces exerted by the float at said limiting positions, and a housing enclosing a space about said switches, said housing being substantially airtight except for a closely fitting opening through which said connecting means extends.

2. A device as defined in claim 1, in which

the opening for the connecting means is protected by a substantially uncompressed packing of a moisture-repellant fibrous material.

5 3. A device as defined in claim 1, in which the opening for the connecting means is protected by a substantially uncompressed packing of wool.

Signed at New York, N. Y., this 21st day of June 1928.

10 JOHN H. DERBY.
